Primary Examiner — Marissa J Cash*Assistant Examiner* — Rebecca Tsehay*(74) Attorney, Agent, or Firm* — HYIP(57) CLAIM

The ornamental design for an electronic cigarette, as shown and described.

DESCRIPTION

FIG. 1 is a front view of an electronic cigarette showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is another perspective view thereof;

FIG. 9 is a front view of an electronic cigarette according to a second embodiment showing my new design;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view thereof; and,

FIG. 16 is another perspective view thereof.

The broken lines depict portions of the electronic cigarette that form no part of the claimed design.
